(57) **CLAIM**

The ornamental design for a mirror, as shown and described.

DESCRIPTION

FIG. 1 is a perspective view of a mirror according to an embodiment of the invention.

FIG. 2 is a front view of a mirror according to an embodiment of the invention.

FIG. 3 is a side view of a mirror according to an embodiment of the invention, the view from the opposite side being a mirror-image thereof; and,

FIG. 4 is a top view of a mirror according to the embodiment of the invention.

The portion of the figures shown in dashed lines are for illustrative purposes only and form no part of the claimed invention.
